(57) **CLAIM**

The ornamental design for a spray pump head, as shown and described.

DESCRIPTION

FIG. 1 is a perspective view of the spray pump head of my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The stippled portions of the spray pump head are of a color other than a white with the non-stippled portions being a white color. The stippled portions provide a color contrast of the parts of the spray pump head design.
